US00D888256S

(12) **United States Design Patent** (10) **Patent No.:** **US D888,256 S**
Del Rossi et al. (45) **Date of Patent:** **** Jun. 23, 2020**

(54) **BANDAGE**

(71) Applicant: **Vomaris Innovations, Inc.**, Tempe, AZ (US)

(72) Inventors: **Joseph Del Rossi**, Phoenix, AZ (US); **Mary Maijer**, Tempe, AZ (US)

(73) Assignee: **Vomaris Innovations, Inc.**, Tempe, AZ (US)

(**) Term: **15 Years**

(21) Appl. No.: **29/682,883**

(22) Filed: **Mar. 8, 2019**

(57) **CLAIM**

The ornamental design for a bandage, as shown and described.

DESCRIPTION

FIG. 1 is a perspective view of a bandage of our design. FIG. 2 is a top view of the bandage of FIG. 1.

FIG. 3 is a bottom view of the bandage of FIG. 1.

FIG. 4 is a first side view of the bandage of FIG. 1.

FIG. 5 is a second side view of the bandage of FIG. 1.

FIG. 6 is a front view of the bandage of FIG. 1; and,

FIG. 7 is a back view of the bandage of FIG. 1.

The broken lines shown in the figures are included for the purpose of illustrating portions of the bandage and form no part of the claimed design. Randomly dashed lines represent surface shading.

1 Claim, 3 Drawing Sheets
